UNITED STATES PATENT OFFICE.

HERBERT FREDERICK BROADHURST, OF LONDON, ENGLAND.

MEANS FOR FILLING BOTTLES.

1,413,960.

Specification of Letters Patent. Patented Apr. 25, 1922.

Application filed December 12, 1921. Serial No. 521,837.

To all whom it may concern:

Be it known that I, HERBERT FREDERICK BROADHURST, a subject of the King of Great Britain and Ireland, and a resident of London, England, have invented a certain new and useful Improvement in Means for Filling Bottles, of which the following is a specification.

This invention relates to filling bottles, 10 tins, or other receptacles by difference of pressure, and is of the kind wherein filling is effected by removing air from the bottle by suction through a nozzle connected to both an exhauster, a liquid supply vessel, 15 and also to the atmosphere.

In an apparatus of the above nature, it has been proposed to employ a nozzle having two tubes adapted to pass into the neck of the bottle and sealed air-tight thereto by 20 a soft washer, and a connection adapted to be opened from the atmosphere, after the bottle is filled, into one of the tubes, preferably the liquid conduit. This connection admits air to the liquid stream when the 25 nozzle and the bottle are being separated, so that the liquid below this connection to the atmosphere or between it and the bottle will flow into the bottle. With this arrangement, the bottle is first sealed and the 30 atmospheric connection closed to establish the flow of liquid under suction into the bottle, and when the bottle is full and the filling nozzle raised, parting the column of liquid by the admission of air through the atmospheric connection must allow the pipes passing 35 through the neck of the bottle to drip when the nozzle is raised, because the whole of the liquid in the two tubes forming the nozzle has to drip out by gravity only under 40 the small head due to the length of the nozzle only.

For a clear understanding of the invention, reference is to be had to the following description and accompanying sheets of 45 drawings, which illustrate a practical embodiment of the means or apparatus employed, and wherein:

Figure 1 is a side view of said apparatus.

Figure 2 is an end view thereof.

Figure 3 is an underside plan view.

Figure 4 is a vertical sectional view illustrative of the application of the said invention.

Like letters of reference indicate corresponding parts in the several figures.

According to the present invention, use is

made of three separate tubes all communicating with the interior of the bottle, viz:—vacuum, suction and breaker pipes.

The purpose of the vacuum pipe is to withdraw air from the bottle.

The purpose of the suction pipe is to conduct liquid from the supply tank to the bottle.

The purpose of the breaker pipe is to admit air to the interior of the bottle after the vacuum is shut off when the bottle is filled and so break the vacuum, correct the level and drain off both the vacuum and filling pipes before the nozzle is raised in the bottle.

In carrying out the invention, and referring first to Figures 1 to 3, the apparatus consists of a head *a* provided with a nearly horizontally disposed filling tube *b* which terminates in a vertically disposed nozzle *c* adapted to be inserted into the neck of a bottle to the level to which said bottle is to be filled.

Besides this, and nearly the same length, 80 is a small tube *d*, termed the vacuum tube, and also another small tube *e*, termed the breaker tube, which just reaches into the neck of the bottle. Round these tubes *c*, *d*, *e*, is arranged a soft washer *f*, of india-rubber 85 or any suitable material, to make an air-tight joint on the top of the bottle.

The filling tube *b* is carried in its nearly horizontal position until clear of the bottle, and then continues as a suction pipe *g* downwardly into a supply tank, which is situated at a lower level than the bottle or bottles to be filled, the vacuum tube *d* being connected up to a pump by which as much of the atmospheric pressure as may be required can 95 be removed from the bottle or the like.

The action is as follows:—The nozzle *c* of the filling pipe *b* is inserted into the neck *h* of the bottle *i*, as in Figure 4, washer *f* seating on the mouth of said bottle, which is supported in any suitable manner. The breaker tube *e* is closed to the atmosphere, i. e., the air lock, by any suitable arrangement of valve, not shown on the drawings. The pump is then set going, and, through the 105 vacuum tube *d*, removes pressure from inside the bottle *i* and also from the filler tube *b*, causing liquid from the supply tank to rise in the suction pipe *g* and to run through the filling tube *b* into the bottle.

When the level of the liquid reaches the end of the vacuum tube *d*, no more air can

be withdrawn from the bottle, and a small quantity of liquid is drawn up by and into the vacuum tube *d*. The vacuum tube *d* is then shut off from the pump by any suitable arrangement of valve, such for example as shown at *x*, but located some distance away from the nozzle, and the breaker tube *e* opened to the atmosphere by valve *y*, breaking the vacuum in the neck of the bottle, with the result that the column of liquid in the suction pipe falls back into the supply tank, drawing back any slight excess of liquid in the neck of the bottle and all the liquid in the filling tube *b* and nozzle *c*, leaving the level of liquid in the bottle exactly at the level of the bottom of the nozzle of the filling tube, at the same time any liquid which has entered the vacuum tube is drawn towards the pump, and may, if desirable, be trapped and removed in any suitable manner, so that when the nozzle is lifted out of the neck of the bottle there is no drip and the bottle is filled cleanly to an exact level.

Any number of bottles can be connected to vacuum and breaker tubes, common to all, and will operate simultaneously, and even if some bottles fill before others, none can overfill and all will fill to the same level, provided all nozzles are of the same length. A cracked bottle will not fill, the only effect being to waste the vacuum on the nozzle of that bottle, the other bottles filling as usual, this action forming an automatic test of the condition of said bottles.

A suction pipe, common to all, can be used for a number of nozzles, i. e. filling tubes, but it is preferably to have a suction tube for each, so that each bottle is syphoned off to a level of its filling tube, and this tube itself emptied by an independent column of liquid.

A pressure below atmosphere in the bottles need not be employed, as it is obvious that the apparatus works by difference of pressures, and both the bottle pressure and the supply pressure may be above the atmosphere, so that this apparatus can be used for bottling gaseous liquids, which have to be filled against a counter-pressure.

In this case the liquid is contained in a

reservoir at pressure, and may be arranged above or below the bottles, and is suitably controlled.

The action is as follows:—When the nozzles are in the bottles, counter-pressure, equal to the pressure in the reservoir, is admitted through the breaker tube. The liquid from the reservoir is turned on, the breaker tubes closed, and then the counter-pressure lowered by means of the vacuum tube until the liquid flows into the bottles up to the end of the vacuum tubes. When counter-pressure equal to the reservoir, if the reservoir is situated below the bottles, or above the pressure in the reservoir if the reservoir is above the bottles, is turned on again through the breaker tubes, the liquid is driven back out of the nozzles again and into the suction tubes, leaving the bottles filled up to the level of the filling nozzles.

I claim:—

1. A device for filling bottles including a filling head having a filler nozzle provided with a sealing gasket, a suction pipe communicating with the filling nozzle, a vacuum pipe also carried by the head and having its open end disposed adjacent the filler nozzle, and a breaker pipe connected with the atmosphere and having an open end located at a point above the outlet end of the vacuum pipe.

2. A bottle filling device including a filling head carrying a filler nozzle, a suction pipe connected with the source of material to be bottled and communicating with the filler nozzle, and vacuum and breaker tubes carried with the filler nozzle and the latter being connected with the atmosphere, and a sealing gasket surrounding the filler nozzle and tubes.

3. A bottle filling device including a filling head carrying a nozzle unit, said nozzle unit including a filler tube in communication with the source of material to be bottled and vacuum and breaker tubes, the latter being connected with the atmosphere and manually controlled valves for said vacuum and breaker tubes.

In testimony whereof I have affixed my signature.

HERBERT FREDERICK BROADHURST.
